UNITED STATES PATENT OFFICE.

DAVID J. BISSELL, JR., OF SPOKANE, WASHINGTON, ASSIGNOR TO OTIS AUTOMATIC TRAIN CONTROL INCORPORATED, OF SPOKANE, WASHINGTON, A CORPORATION OF WASHINGTON.

MANUALLY-OPERABLE VALVE FOR AUTOMATIC TRAIN-CONTROL APPARATUS.

Application filed May 1, 1923. Serial No. 635,899.

To all whom it may concern:

Be it known that I, DAVID J. BISSELL, Jr., a citizen of the United States, and resident of Spokane, in the county of Spokane and 5 State of Washington, have invented certain new and useful Improvements in Manually-Operable Valves for Automatic Train-Control Apparatus, of which the following is a specification.

10 My invention relates to automatic train control apparatus of the type including a ramp valve operable by suitable track mechanism to, at predetermined times, cut off the supply of air to the usual train line 15 or brake pipe and simultaneously vent the latter to the atmosphere, thereby to cause an application of the brakes and consequent stoppage of the train, such apparatus being disclosed in my copending application serially numbered.

More particularly my invention relates to a manually operable valve that is adapted to be connected with a ramp valve and with the supply and train line pipes of an ordinary 25 air brake system, so that upon its manipulation, following actuation of the ramp valve, train line pressure may be prevented from exhausting to the atmosphere and the supply may be placed in communication with the 30 train line whereby the train, instead of being brought to a stop, may proceed and be under the control of the engineman.

My inventive idea is capable of embodiment in different mechanical structures, one 35 of which is illustrated in the accompanying drawings. It is to be understood, however, that the structure illustrated is merely intended as a disclosure of my invention in a form to render its purpose and mode of 40 operation clear, and that various changes and desirable additions may be made in and to the same within the spirit and scope of my invention as defined in the appended claims.

In the drawings the figure is a diagrammatic view showing my improved valve in section and operatively connected with a ramp valve and with the supply and train line pipes of an ordinary air brake system.

Referring to the drawing in detail, it will 50 be observed that my improved manually operable valve consists of a casing 10 provided with a pair of valve chambers 11 and 12 which valve chambers have arranged therein, respectively, valves 13 and 14 that are car-

ried by a common stem 15, whereby they are 55 movable in unison. Surrounding said stem and reacting from the casing against valve 13 is a coil spring 16 that holds said valve normally off its seat 17 and valve 14 normally closed with respect to a port 18 in the 60 casing that opens into valve chamber 12.

A knob 19 is provided on stem 15 whereby said stem may be manipulated to seat valve 13 and simultaneously move valve 14 to uncover port 18, in which event communication will be established through valve chamber 12 between port 18 and another port 20. Normally, however, spring 16 urges valve 13 off its seat 17 and valve 14 closed with respect to port 18, thereby nor- 70 mally to provide communication through valve chamber 11 between a port 21 and an atmospherically opening port 22, and at the same time deny communication between ports 18, 20.

The ramp valve with which my improved manually operable valve is adapted for association may be of any preferred construction, its only essentials being that in the first instance it establishes communication 80 normally between the usual supply and train line pipes and deny communication of the train line pipe with my manually operable valve, and in the second instance, when it is actuated by a ramp device, that it place the 85 train line in communication with my manually operable valve. To this end said ramp valve is shown as including a casing 23 within which is rotatably mounted a plug 24, which plug is provided with a pair of relatively communicating ports 25, 26 adapted in a normal position of the plug to align respectively with a pair of ports 27, 28 in the casing 23, and in a ramp actuated position of the plug to align respectively with a port 29 also formed in the casing and aforesaid port 27. Depending from the plug 24 is a shoe 30 that is adapted for contact with a ramp device thereby to actuate the plug from its normal position to align ports 100 25, 26 with ports 29, 27.

Connecting port 29 of the ramp valve with port 21 of my manually operable valve is a pipe 31, while connecting port 28 of the ramp valve with a suitable source of pressure supply is a pipe 32, which pipe 32 is connected by a branch pipe 33 with port 20 of my manually operable valve. The train line

pipe 34 is connected by a branch pipe 35 with port 27 of the ramp valve and by another branch pipe 36 with port 18 of my manually operable valve.

5 In view of the foregoing, the operation of my invention is apparent and as follows: Upon actuation of the shoe 30 of the ramp valve to align ports 25, 26 in the plug with ports 29, 27 in the casing, pipe 31 is placed 10 in communication through said ports with pipe 35, and as a consequence, the air pressure in the train line pipe is vented to the atmosphere through the normally open port 22 in the manually operable valve. Thus 15 the brakes will be applied and the train brought to a stop unless the engineman is alert and manipulates the manually operable valve to seat valve 13 and close port 22 and thus prevent the escape of train line 20 pressure. If valve 13 is seated, valve 14 simultaneously is opened with respect to ports 18, 20 and communication thus is restored 25 between the supply pipe and the train line, whereby the control of the train is restored 30 to the engineman. Preferably a speed control valve is associated with pipe 31, so that upon actuation of the ramp valve and manipulation of my manually operable valve to 35 prevent the escape of train line pressure and restore control of the train to the engineman, it is impossible to increase the speed of the train above a predetermined low rate, but as the provision of a speed control valve is optional and does not affect the operation 40 of my manually operable valve, it has not been shown.

I claim:

1. In automatic train control apparatus, the combination with the train pipe and the 40 supply pipe of an ordinary air brake system, of means automatically operable at predetermined times to cut off the supply to and vent said train pipe, and a valve device 45 manually operable and effective following operation of said automatic means, to pre-

vent venting of the train pipe through said automatic means and to simultaneously place the supply pipe in communication with the train pipe.

2. In automatic train control apparatus, 50 the combination with the train pipe of an ordinary air brake system, of a valve including means constantly urging the same to open position, and means automatically operable at predetermined times to vent the train pipe through said valve, the latter being 55 manually operable to closed position and when so operated being held closed by the pressure of fluid in said train pipe.

3. In automatic train control apparatus, 60 the combination with the train pipe of an ordinary air brake system, of a valve including a spring constantly urging the same to open position, and means automatically operable at predetermined times to vent 65 the train pipe through said valve, the latter being manually operable to closed position and when so operated being held closed by the pressure of fluid in said train pipe, and adapted to open automatically under the influence of said spring when the pressure of fluid in the train pipe is reduced. 70

4. In automatic train control apparatus, 75 the combination with the train pipe and the supply pipe of an ordinary air brake system, of a normally open valve and a normally closed valve relatively connected for movement in unison whereby the latter is opened when the former is closed, and means automatically operable at predetermined times to 80 vent the train pipe through said normally open valve, the normally closed valve being connected with the supply pipe and the train pipe whereby communication is established between these pipes when the normally open valve is closed. 85

In testimony whereof I hereunto affix my signature.

DAVID J. BISSELL, JR.
